TRIGGER MECHANISM FOR AUTOMATIC FIREARMS

Erwin Hepperle, Zurich, Switzerland, assignor to
Verwaltungsgesellschaft der Werkzeugmaschinen-
fabrik Oerlikon, Zurich-Oerlikon, Switzerland

Application February 26, 1946, Serial No. 650,174
In Switzerland February 28, 1945

5 Claims. (Cl. 89—150)

1

Automatic fire arms include in the trigger mechanism devices intended to catch the breech block after the release of the last shot. It is essential in such devices that the contact between catch hook and catch nose should be established over the whole face so as not to damage the edges and impair in a short time the correct working of the catch device.

In a known device of this kind the catch hook is pressed by a spring out of the range of the catch nose; by releasing the firing or sear actuating lever a pawl indirectly causes the projection of the catching face of the sear or catch hook into the path of the catch nose of the breech block whereby the catching face of the sear is brought within the range of a nose provided on the breech block.

Practice has shown, however, that this known device, as a result of vibrations in the trigger mechanism which cause a back spring action of the catch devices, does not guarantee with absolute reliability a full-face contact of catch hook and catch nose, thus making it impossible to avoid damage to the faces and more particularly to the edges. Moreover, the set-up of this known design is complicated, due to the fact that the pawl actuated by the release of the firing lever controls only indirectly—i. e. over various other members—the projecting of the catching face of the sear or catch hook into the path of the catch nose of the breech block.

The present invention relates to a trigger mechanism reliably securing full-face contact of catch hook and catch nose, and of extremely simple design compared with known types.

In the trigger mechanism for automatic fire arms according to the present invention a pawl is articulated on the locking lever or sear, which pawl can be actuated during the forward travel of the breech block both from the firing or sear actuating lever and from a control face provided on the breech block, the pawl having surfaces which in the end positions of its free travel, come into contact with corresponding surfaces on the sear, so that the latter must compulsorily carry out the movements of the pawl as directed by the sear actuating lever or the catch nose on the breech block. The pawl can suitably be of such design that, in the locked position of the breech, it lies on the latter, thus securing the locking lever or sear and rendering impossible the release of the breech through shocks or the like.

The accompanying drawing shows in Figs. 1-7 a constructional example of realisation of the present invention.

2

Fig. 1 is a schematical representation, in section, of an automatic fire arm;

Fig. 2 is a section through the trigger mechanism, the breech block being in locked position;

Fig. 3 is a section through the trigger mechanism as the sear actuating lever is starting its rotating motion;

Fig. 4 is a section through the trigger mechanism, with sear actuating lever completely pulled and breech block released;

Fig. 5 is a section through the trigger mechanism, with released sear actuating lever, at the moment when the breech block locking motion is being started;

Fig. 6 is a view from above on the trigger mechanism;

Fig. 7 is a section along the line 7—7 in Fig. 6.

According to Fig. 1 the barrel 1 is inserted in known manner in a breech casing 2 by means of a bayonet joint. In the breech casing 2 glides the breech block 3 on which acts the recuperating spring 4. The breech block 3 is fitted with a nose 3a which engages with the locking face 5 of the locking lever or sear 6. The sear 6 is pivotally mounted on a pin 7 in the trigger casing and is responsive to the action of a spring 8 which has the constant tendency to force it into the position shown in Fig. 4, i. e. out of the way of the catch nose 3a. On the side opposite to the locking face 5 the sear 6 is of fork shape and carries the pawl 10 movably seated by means of the pin 9 to which it is secured. In a hole of the sear 6 is located a spring 11 pressing against the pawl 10 and attempting to force it into the position shown in Figs. 2 and 5. The pawl 10 is fitted in the sear 6 in such a manner that after a short free travel either its face 10a comes into contact with the corresponding face 6a of the sear, or its face 10b with the face 6b of said sear.

40. The sear actuating lever 12 is mounted by means of pin 13 in the trigger casing and is actuated in known manner, not represented here. A projection 12a of the sear actuating lever 12 is responsive to the action of a spring 14 located in the trigger casing, which on release of the trigger moves the lever back into rest position. The lever 12 acts by means of a finger 15 on the pawl 10.

45. The pin 9 by means of which the pawl 10 is seated in the sear 6 has on one side an enlarged head 16. This head 16 is provided with a slot 17 into which catches the pin 18 of the safety lever 19. The safety lever 19 is spring-loaded by a spring 20 which forces the pin 18 into the slot 55 17 in the head 16 of the pin 9. By lifting the pin

18 of safety lever 19 against the pressure of the spring 20, the lever 19 can be swung round the pin 13 on which it is pivotally mounted.

The breech block 3 is furthermore provided with a cam face 21 which is adapted to engage the pawl 10 when the latter is in the position shown in Fig. 5.

The trigger mechanism described above operates as follows:

Before actuating the sear actuating lever 12 the safety lever 19 which keeps locked the pivot pin 9 of the pawl 10—the latter, in the locked position of the breech block, securing at the same time the sear 6—must first be shifted. This is done by pulling the pin 18 out of the slot 17 of the head 16 in the pin 9, after which the safety lever 19 can be swung around the pin 13. The pawl 10 is now released, by clockwise rotation of sear actuating lever 12, whereby the latter's finger 15 will cause the pawl 10 to rotate counterclockwise round the pin 9. As a result, the spring 11 is first compressed until the pawl 10, with its face 10b, comes into contact with the corresponding face 6b of the sear 6 (Fig. 3). On further rotation the sear actuating lever 12 also rotates the sear 6 by way of the pawl 10 which is now in contact with the sear at 6b. As a result, the locking face 5 of the sear 6 moves out of the catch nose 3a of the breech block 3. This position is shown in Fig. 4. The breech block now moves forward through the action of spring 4 and firing begins. If now the lever 12 is kept in its rotated position, as shown in Fig. 4, continuous fire is kept up. It will be understood that the construction of the breech block is such that the nose 3a does not strike the pawl 10. As soon, however, as the lever 12 is released, the pawl 10, under the action of the spring 11, takes up an erect position, so that its face 10a comes into contact with the face 6a of the sear 6. In this position, the pawl protrudes into the path of the guiding face 21 since the sear is still held in its rotated position by the spring 8. After its rear reversal, that is, when moving forwardly toward the gun breech, the breech block, with its guiding face 21, actuates the pawl 10, thus pressing upwardly the pawl-carrying end of the sear 6 and bringing the locking face 5 within range of the catch nose 3a on the breech block 3.

The present invention provides with simple means a trigger mechanism reliably securing full-face engagement of the locking face 5 of the sear with the catch nose 3a of the breech block 3, and affording in addition absolute security against the accidental release of the breech block through vibrations.

I claim:

1. Trigger mechanism for automatic firearms, comprising a pivoted sear movable into position to lock the breech block, a pawl pivotally mounted on said sear so as to have limited free rotational movement in opposite directions relative to the sear, said pawl having surfaces which in the end position of its free movement come into contact with corresponding surfaces on the sear, whereby

on further actuation of the pawl in either direction the sear must follow the movements of the pawl about the axis of the sear, a breech block having a cam surface adapted to engage the pawl, when it is at one of its limits of free rotational movement, a lever arranged also to actuate said pawl, actuation of the pawl by said lever causing the sear to rotate and release the breech block, and actuation of the pawl by the cam surface of the breech block causing the sear to return into locking position.

2. Trigger mechanism according to claim 1 including a spring disposed on the sear and acting to urge the pawl into the path of the cam surface of the breech block.

3. Trigger mechanism according to claim 1, wherein the breech block is provided with a catch nose into whose path the sear is moved when the pawl is actuated by the cam surface of the breech block and has been caused to rest on top of the breech block, whereby the sear is locked against the catch nose of the breech block, and a spring acting on said sear, said spring retaining the sear in its rotated position after the sear actuating lever has been released, until the sear is returned into locking position by the pawl.

4. Trigger mechanism for automatic firearms, comprising a pivoted sear movable into position to engage the breech block to lock the same against forward movement, a spring normally urging the sear into inactive condition, a sear actuating lever for moving the sear out of locking position, a pawl interposed between the sear actuating lever and the sear and pivotally mounted on the sear, said pawl having limited pivotal movement relative to the sear in opposite directions and carrying the sear with it about the pivotal axis of the sear when urged in either direction beyond the limit of its relative movement with respect to the sear, said sear actuating lever engaging the pawl and moving the sear out of locking position on pulling of the trigger, and a spring moving said pawl relatively to the sear upon release of the trigger and into position for engagement by a cam surface on the breech block, whereupon said pawl and sear are rotated as a unit about the pivotal axis of the sear to bring the latter into locking engagement with the breech block.

5. Trigger mechanism according to claim 4 wherein the pawl is so dimensioned that it rests on the breech block in the locked position of the latter and thus serves to hold the sear in locking position against the action of the first mentioned spring.
